ABSTRACT

In typical crossbar switches, selection operators move flexible fingers to restricted areas within openings of selected operate cards, and subsequent operation of hold actuators against the fingers operate the selected cards. According to this disclosure, the ends of the flexible fingers that are to be engaged by operated selection operators are bent to function as levers that are rotated quite readily as a result of the twist of the long portions of the flexible fingers. The torsional spring characteristic provided by the levers permits the selection operators to operate fully during preselection without requiring much more than normal operating force.

ACTUATORS WITH TORSION ARMS FACILITATING PRESELECTION IN CROSSBAR SWITCHES

BACKGROUND OF THE INVENTION

This invention relates to electromagnetically operated switches of the crossbar type and particularly to an improvement in their actuators for preselecting crosspoints.

A crossbar switch to which the present improvement is applicable is described in U.S. Pat. No. 3,445,795 issued to R. P. Holtfreter et al. on May 20, 1969. Each crosspoint comprises a plurality of contacts extending through an operate card. The card for each of the crosspoints is urged to an unoperate position by a spring, and it is moved to an operate position by cooperation of a selection actuator, a flexible finger, and a hold actuator. Each flexible finger passes through an opening in a respective card, the opening having a shape that determines the amount of free movement of the finger in a longitudinal direction of the card according to the lateral placement of the finger. That portion of an opening that allows longitudinal movement of a finger without moving the card is said to be an unrestricted area, and that portion that does not allow longitudinal movement is a restricted area. The flexible fingers are normally biased toward the unrestricted areas, and until the fingers are moved to a restricted area, movement of the flexible fingers by operation of the hold actuators does not move the cards from their unoperate positions. When the flexible fingers are individually selected first by operation of the selection actuators, they are moved laterally into the restricted areas, and subsequent operations of their hold actuators against the flexible springs cause them to move the operate cards longitudinally to their operate position. After any crosspoint is operated it is held operated as long as its hold actuator is operated.

Usually, a selection actuator is not operated to make a new selection until after the associated hold actuators and the flexible fingers controlled thereby have been returned to normal, and a previously selected crosspoint has been released. However, faster operation is achieved in present switching systems by "preselection". Preselection causes a selection actuator to be operated before an associated hold actuator has had time to return to its normal position. While the hold actuator is still in its operate position, it is pressing against unselected fingers to hold them in a part of the unrestricted area that is opposite to that where the fingers are normally located. The movement of these fingers is therefore restricted laterally as well as longitudinally until the hold actuator has returned from its operate position. The flexible fingers of crosspoints, other than those still operated from a previous selection, that are common to the hold actuator and the selection actuator must bend transversely an abnormal amount to permit full lateral operation of the associated selection actuator. Therefore preselection is prevented unless the actuators can provide greater force than that normally required.

SUMMARY OF THE INVENTION

Crossbar switches according to this invention have an improved arrangement of selection operators and flexible fingers to permit preselection without requiring use of excessive force by the selection actuators. Only moderate force is required to operate the selection actuators because the flexible fingers have levers against which the selection operators of the selection actuators press during their operation. The selection operators are straight members attached to selection actuator bars to contact levers at a distance from the axes of the respective flexible fingers. As the selection operators are moved against the levers, the flexible fingers tend to twist to allow the levers to rotate. The flexible fingers can usually be quite easily moved laterally by operation of the selection operators before the flexible fingers twist more than a slight amount. To compensate for increased resistance to bending during preselection while the flexible fingers are constrained from lateral movement where they pass through their cards, the flexible fingers twist to allow rotation of their levers without placing a

heavy load on the magnets that operate the selection operators. As a hold actuator returns to its normal position, the selected flexible finger that is in a constrained position, moves along the curved side of the opening to a select position where the torsional strain caused by pressure of the selection operator is small.

BRIEF DESCRIPTION OF THE DRAWING

- 10 FIG. 1 is an oblique view of fragmentary select and hold actuators of a crossbar switch to show preselection according to this invention; and
- 15 FIG. 2 is a view of the upper right actuators of FIG. 1 as they appear for an instant while the hold actuator is releasing during preselection.

DESCRIPTION OF THE PREFERRED EMBODIMENT

A plurality of crosspoints represented by the crosspoints 11-18 of FIG. 1 are mounted in a rack and operated by selection and hold magnets in a manner similar to that described in U.S. Pat. No. 3,445,795 to which reference has been made above. The contacts and cards according to the present drawing are shaped somewhat differently from those shown in the patent to facilitate manufacture. The selection operators and the flexible fingers have been shaped according to this invention to provide preselection without unduly loading the selection magnets.

Each of the crosspoints 11-18 has cards 24-31 respectively to operate contacts 19 to engage fixed contacts that are not shown. A crosspoint to be operated is selected by a selection actuator, and is then operated by a hold actuator assembly. For example, any of the crosspoints 11-14 after being selected can be operated by the operation of the hold bar 20 to move their respective cards 24-27, and likewise any of the crosspoints 15-18 after being selected can be operated by operation of the hold bar 21.

Which one of the cards 24-31 is to be operated by operation of a hold bar is determined by the position of a respective flexible finger that passes through an opening in the card. Each of the openings located at one end of the card has in general a triangular shape with a straight side in the longitudinal direction and an adjacent straight side in the direction across the card. The third side is curved inward toward the right angle between the straight sides so that the overall shape resembles a sharply curved boomerang. The end of the curve side that joins the adjacent lateral side is substantially parallel to the lateral side and is offset slightly therefrom to receive the respective flexible finger during selection of the card for operation.

In a preferred embodiment, the flexible fingers for two adjacent cards are joined in a bight, and the bight is fixed to a mounting button. For example, the fingers 32 and 33 are joined by a bight 40 that is used to mount the fingers on a fixed button 41. The free end of each of the fingers 32-39 has a portion 42-49 respectively bent at right angles to the rest of the finger. The bent portions of each of the joined pair of fingers are parallel to the longitudinal direction of the cards and are spaced apart slightly to receive a selection operator 50-53 between them. The point at which a selected finger is contacted by an operator is at a distance from the long portion of the finger, and therefore the bent portion of the finger functions as a lever and tends to twist the finger. Each long finger is normally constrained only at its bight 40 by the inward tension of it and the other finger of a pair, and it can be moved outwardly quite easily by its selection operator from its normal position to its operate position. During normal operation, the force required to move the finger laterally is not enough to cause much twist of the finger, but during preselection as described below, the fingers are constrained much closer to the selection operator, and with a moderate additional force, the flexible finger twists to prevent excessive resistance to full operation of the selection operator.

In FIG. 1, the positions of the flexible fingers for the different crosspoints are shown according to the operation of their respective selection actuators and hold actuators. For the crosspoints 13 and 14, the selection bar 56, the hold bar 20, and the flexible fingers 34 and 35 are shown in their normal positions. At the crosspoint 12, the selection bar 57 has been rotated away from the flexible finger 33 of the crosspoint 12 to move its operator 50 against the adjacent flexible finger 32. Therefore, the finger 33 is also in its normal position, but the finger 32 has been moved laterally within its opening in the card 24 to the operate position where it is constrained longitudinally in the card. As described above, the force required to move the finger freely in its opening is too small to cause much twist in the finger 32. Since the hold bar 20 is unoperated, the positioning of the finger 32 has no effect on the position of the card 24.

The hold bar 21 common to the crosspoints 28-31 is shown operated. Since neither of the flexible fingers 38 and 39 of the crosspoints 17 and 18 has been moved laterally from its normal position, the hold bar 21 has moved both of them freely longitudinally within the openings through which they extend while the cards 30 and 31 remain in their normal positions.

To illustrate the advantage of utilizing the torsional spring characteristic of the flexible finger 36, the positions of the crosspoints 15 and 16 are shown when the hold bar 21 is still operated from a previous selection of the crosspoint 16, and the selection bar 57 is operated to "preselect" the crosspoint 15. The hold bar 21 is to be returned to normal instantly and then to be operated again immediately for operating the selected crosspoint 15.

The finger 37 of the crosspoint 16 is still retained in the restricted area of its opening in the card 29 by the hold bar 21, and the card 29 is still in its operate position. As the hold bar 21 returns to normal, the flexible finger 37 returns by its own spring force to its normal position in the right angle of its opening.

The rotation of the bent portion 46 of the flexible finger 36 permits operation of the crosspoint 15. Since the hold bar 21 has not had time to return to normal from its previous operation, the flexible finger 36 is retained in the area between its longitudinal side and its curved side 58. While the finger 36 is retained and the selection bar 57 is operated to force the operator 51 against the bent portion 46 of the finger, the long portion of the finger offers much greater resistance than usual to bending because it is constrained by the card at a point near the selection operator. As the force becomes somewhat greater than that required to bend a normally positioned flexible finger, the bent portion or lever 46 rotates to relieve the force on the actuator (not shown) that operates the select bar 57.

In FIG. 2, the position of the flexible finger 36 within its opening in the card 28 is shown at the instant when the hold bar 21 has returned about halfway to its normal position. The force caused by the rotation of the bent portion 46 causes the flexible finger 36 to follow the curved side 58 from the longitudinal side to the lateral side where the longitudinal motion

of the finger 36 is restricted in the card 28. As the finger travels to its normal operate position, the bent portion 46 rotates until it is substantially parallel with the longitudinal direction of the card 28. The position of the finger 36 of the crosspoint 15 therefore becomes similar to that shown for the finger 32 of the crosspoint 11. The crosspoint 16 is now released, and the hold bar 21 operates again to operate the crosspoint 15 to the position shown for the formerly operated crosspoint 16 in FIG. 1.

10 I claim:

1. In a crossbar switch assembly of the type having a plurality of actuator cards, a plurality of movable crosspoint contacts extending through each of said cards, means biasing said cards individually to an unoperated position, said cards being translatable to an operated position to actuate respective ones of said contacts, each of said cards having an opening with an unrestricted area and a restricted area, a resilient finger extending substantially perpendicularly through each of said openings, each of said fingers being biased toward said unrestricted area, a plurality of rigid selection fingers each selectively operable to move a corresponding one of said resilient fingers in opposition to its bias to a restricted area of the corresponding card, and a hold actuator operable to impart a movement to said resilient fingers such as to cause only the ones of said actuator cards having the resilient finger in the restricted area to be translated from an unoperated to an operated position;

15 2. The improvement comprising a bent portion forming a lever at the end of each said resilient finger, each of said selection fingers being arranged to engage the bent portion of the corresponding resilient finger at a point to provide torsional leverage on said resilient finger, and the twisting of said resilient finger allowing movement of the selection finger with a moderate amount of force when said resilient finger is positioned in said unrestricted area of said actuator card during preselect operation.

20 3. The improvement in a crossbar switch assembly as claimed in claim 1 wherein said opening in each of said actuator cards is shaped like a sharply curved boomerang, said unrestricted area being one arm of said opening extending longitudinally along said actuator card to permit freedom of movement of the corresponding one of said resilient fingers in the longitudinal direction of said card, and said restricted area being the other arm of said opening extending across said actuator card to prevent free longitudinal movement of the corresponding resilient finger therein.

25 4. The improvement in a crossbar switch assembly as claimed in claim 1 wherein said resilient fingers are joined in pairs by a bight at one end of each pair, and said bent portion of each of said fingers is bent at a right angle at the opposite end thereof.

30 5. The improvement in a crossbar switch assembly as claimed in claim 1 wherein said resilient finger is substantially L-shaped, and the corresponding selection finger engages the base of said L to provide torsional leverage on said resilient finger.
